ABSTRACT OF THE DISCLOSURE

An integrated circuit directional coupler having two conducting lines separated from a semiconductor layer by an insulating coating on the semiconductor layer. A conducting ground plane is situated on the other side of the semiconductor. Coupling from one line to the other allows a small, efficient, directional coupler to be constructed based on the transmission line.

BACKGROUND OF THE INVENTION

This invention is in the field of integrated circuit directional couplers.

A directional coupler is a system containing a primary line and a secondary line arranged such that an incident voltage waveform into one end of the primary line is coupled to the other end of the primary line and to both ends of the secondary line in an amount dependent upon the structure of the coupler, the frequency of the waveform and the direction of travel of the wave.

Stripline directional couplers have been designed previously to include transmission lines separated from one or more ground planes by one or more layers of dielectric material.

SUMMARY OF THE INVENTION

This invention is particularly concerned with a stripline directional coupler for use with integrated circuits. In the present invention it has been found that by separating a pair of parallel transmission lines from a ground plane with an insulator-coated semiconductor, the directional coupler thus constructed yields more ways of energy distribution than does the conventional stripline directional coupler with dielectric separation. The disclosed directional coupler, when excited at the rear end of the primary line, can provide an output to the near end or the far end of the secondary line, which is not possible with conventional directional couplers utilizing homogeneous dielectric media.

It is an object of this invention to provide a directional coupler mainly for use on integrated circuit chips.

It is a further object of this invention to provide a directional coupler using insulated semiconductor material as a base.

BRIEF DESCRIPTION OF THE DRAWINGS

FIGURE 1 illustrates the basic structure of the present invention; and

FIGURE 2 illustrates an equivalent circuit representation of the structure of FIGURE 1.

DESCRIPTION OF THE PREFERRED EMBODIMENTS

FIGURE 1 illustrates an integrated circuit directional coupler according to the present invention. A wafer 5 of semiconductor material forms the body of the integrated circuit directional coupler as well as that of other components located in the same chip. In the preferred embodiment, this semiconductor material is silicon although other semiconductor materials may be used. A layer 4 of

2

insulating material is affixed to one side of wafer 5. In the preferred embodiment, this insulating material is silicon dioxide which can be formed by well-known techniques directly on the surface of silicon wafer 5. However, other insulating materials may be used and are within the scope of this invention. A layer 3 of conducting material forming a ground plane is affixed to the other side of wafer 5. Two transmission lines 1 and 2 of conducting material are shown affixed to the insulating layer 4. The conducting material is preferably metallic and may be deposited aluminum.

The thickness t , width b , and spacing d of the transmission lines may be varied to vary the transfer function of the illustrated system. The ordinary transmission line in this system is 1 mil in width b and 1 micron in thickness t . The thickest preferred line is 2 microns thick and could be 2 mil wide.

The transmission line illustrated in FIGURE 1 is especially suited for use as a directional coupler in an integrated circuit. A single line on top of an integrated circuit chip has a virtual ground plane located in the semiconductor substrate but near the $\text{SiO}_2\text{-Si}$ boundary in determining the transmission line capacitance. However, in determining the transmission line inductance, the metallic ground plane such as layer 3 in FIG. 1 serves as the current return path. The capacitance is generally large because the oxide layer is very thin and the inductance is also large because the thickness of the semiconductor substrate may be quite large in comparison with the transmission line width b . As a result, a single transmission line on IC chip will have a large propagation delay because it has a large capacitance and a large inductance. Also as a result, two adjacent parallel lines on IC chips will have a negligible capacitive coupling by choosing $h_1 \ll d$ and a large inductive coupling by choosing $h_2 \gg d$. In other words, the coupling between two adjacent lines on IC chip is dominated by inductive couplings. The line as illustrated has a large inductance and capacitance which causes a large delay on the line. This extra delay allows an effective directional coupler to be constructed with a much shorter transmission line than is possible with conventional transmission lines.

FIGURE 2 illustrates an equivalent transmission line circuit useful in analyzing the effect of using the structure of FIGURE 1 as a directional coupler. Although the structure of FIGURE 1 is generally useful as a directional coupler, it is possible to vary the effectiveness of the coupling by varying the parameters of the structure.

There are two coupling coefficients between two transmission lines, namely the capacitive coupling coefficient k_C and the inductive coupling coefficient k_L . These coefficients are defined as follows

$$k_L = \frac{L_m}{\sqrt{L_{11}L_{22}}}$$

$$k_C = \frac{C_m}{\sqrt{(C_{11}+C_m)(C_{22}+C_m)}}$$

where L_m and C_m are mutual inductance and mutual capacitance respectively and where L_{11} , L_{22} , C_{11} and C_{22} are the self inductances and self-capacitances of lines 1 and 2 respectively in the presence of the other line.

Because there is negligible capacitive coupling and a large inductive coupling in the directional coupler according to the present invention k_L is much larger than k_C . In the conventional directional coupler using a homogeneous dielectric, k_L equal k_C , thus causing all wave propagation to be at a single velocity. But in the present invention, there is a slow velocity wave and a fast velocity wave. The delay in the directional coupler appears different to the two waves of different velocity.

Because of the symmetry of the two lines of the directional coupler, one may assume that the self-inductance of the two lines are equal (i.e., $L_{11}=L_{22}$) and that the self-capacitance terms of the two lines are equal (i.e., $C_{11}=C_{22}$). Define terms C and L such that

$$L=L_{11}=L_{22}$$

and

$$C=C_{11}=C_{22}$$

In the equivalent circuit of FIGURE 2, v_1 is the voltage on line 1, where $v_1(o)$ is at the input end and $v_1(l)$ is at the output end; v_2 is the voltage on line 2 where $v_2(o)$ is at the input end and $v_2(l)$ is at the output end. The distance along the line is given by x , where the input end is $x=o$ and the output end is $x=l$.

From the basic coupling equations of the lines

$$\begin{aligned} -\frac{\partial v_1}{\partial x} &= L_{11} \frac{\partial i_1}{\partial t} + L_m \frac{\partial i_2}{\partial t} \\ -\frac{\partial v_2}{\partial x} &= L_m \frac{\partial i_1}{\partial t} + L_{22} \frac{\partial i_2}{\partial t} \\ -\frac{\partial i_1}{\partial x} &= C_{11} \frac{\partial v_1}{\partial t} - C_m \frac{\partial v_2}{\partial t} \\ -\frac{\partial i_2}{\partial x} &= -C_m \frac{\partial v_1}{\partial t} + C_{22} \frac{\partial v_2}{\partial t} \end{aligned}$$

where t is time, and assuming that $k_C \ll k_L$, the following three equations can be derived to show the transfer functions of the directional coupler in each of the three possible directions:

$$\frac{v_2(o)}{v_1(o)} = \left(\frac{1}{\Delta} \right) \frac{2}{\eta^2} (1-\eta^2) [(1+\eta)^2 e^{-\lambda_1 l} + (1-\eta)^2 e^{\lambda_1 l} - (1-\eta)^2 e^{-\lambda_3 l} - (1-\eta)^2 e^{\lambda_3 l}]$$

$$\frac{v_2(l)}{v_1(o)} = \left(\frac{-1}{\Delta} \right) \frac{4}{\eta} [(1+\eta)^2 e^{-\lambda_1 l} - (1-\eta)^2 e^{\lambda_1 l} - (1+\eta)^2 e^{-\lambda_3 l} + (1-\eta)^2 e^{\lambda_3 l}]$$

$$\frac{v_1(l)}{v_1(o)} = \left(\frac{-1}{\Delta} \right) \frac{4}{\eta} [-(1+\eta)^2 e^{-\lambda_1 l} + (1-\eta)^2 e^{\lambda_1 l} - (1+\eta)^2 e^{-\lambda_3 l} + (1-\eta)^2 e^{\lambda_3 l}]$$

The following equations define additional terms used in the transfer function equations:

$\omega = 2\pi$ times input frequency

$$\beta_o = \sqrt{LC}$$

$$\eta = 4 \sqrt{\frac{1-k_L}{1+k_L}}$$

$$\lambda_1 \simeq -j\beta_o \sqrt{(1+k_L)}$$

$$\lambda_3 \simeq -j\beta_o \sqrt{(1-k_L)}$$

$$\lambda_s = \lambda_1 + \lambda_3$$

$$\lambda_f = \lambda_1 - \lambda_3$$

$$Z = \sqrt{\frac{L}{C}}$$

which is the characteristic impedance of the line

Y_s is the admittance of the slow wave mode

Y_f is the admittance of the fast wavemode

and where

$$Y_s = \frac{1}{\sqrt{1+k_L}} \sqrt{\frac{C}{L}}$$

$$Y_f = \frac{1}{\sqrt{1+k_L}} \sqrt{\frac{C}{L}}$$

$$Z_L = \sqrt{\frac{L}{C}} 4 \sqrt{(1-k_L^2)} = \sqrt{\frac{Y_s Y_f}{1-k_L^2}}$$

EXAMPLE

15 Assume a directional coupler with

$$k_C \ll k_L = \frac{L_m}{L} = 0.8$$

20 $l = 0.05$ meter

$$L = 10 \text{ nh./cm.} = 10^{-6} \text{ henry/m.}$$

$$C = 4 \text{ pf./cm.} = 4 \times 10^{-10} \text{ farad/m.}$$

25 Then

$$Z = \sqrt{\frac{L}{C}} = 50 \text{ ohms}$$

$$30 Z_L = \sqrt{\frac{L}{C}} \sqrt{1-k_L^2} = 38.8 \text{ ohms}$$

$$35 \eta = 4 \sqrt{\frac{1-k_L}{1+k_L}} = 0.58$$

If the chosen frequency is 560 mHz., then

$$\beta_o = \omega \sqrt{LC} = 22.4\pi \text{ sec./m.}$$

$$\lambda_1 l = -j\beta_o \sqrt{1+k_L} l = -j \frac{3\pi}{2}$$

$$\lambda_3 l = -j\beta_o \sqrt{1-k_L} l = -j \frac{\pi}{2}$$

$$\lambda_s l = (\lambda_1 + \lambda_3) l = -j2\pi$$

$$\lambda_f l = (\lambda_1 - \lambda_3) l = -j\pi$$

$$50 e^{\pm \lambda_1 l} = \mp j \frac{3\pi}{2} = \cos \frac{3\pi}{2} \mp j \sin \frac{3\pi}{2} = \pm j$$

$$e^{\pm \lambda_3 l} = e^{\mp j \frac{\pi}{2}} = \cos \frac{\pi}{2} \mp j \sin \frac{\pi}{2} = \mp j$$

$$55 e^{\pm \lambda_s l} = e^{\pm j^2 \pi} = \cos 2\pi \mp j \sin 2\pi = 1$$

$$e^{\pm \lambda_f l} = e^{\mp j\pi} = \cos \pi \mp j \sin \pi = -1$$

60 therefore:

$$\frac{v_2(o)}{v_1(o)} = 0.5$$

$$\frac{v_2(l)}{v_1(o)} = j 0.87$$

$$\frac{v_1(l)}{v_1(o)} = 0$$

$$\Delta = \begin{vmatrix} 1 & 1 & 1 \\ (1-Y_s Z_L) e^{\lambda_1 l} (1+Y_s Z_L) e^{-\lambda_1 l} & (1-Y_f Z_L) e^{\lambda_3 l} (1+Y_f Z_L) e^{-\lambda_3 l} \\ (1+Y_s Z_L) & (1-Y_s Z_L) & -(1+Y_f Z_L) \\ (1-Y_s Z_L) e^{\lambda_1 l} (1+Y_s Z_L) e^{-\lambda_1 l} & (1-Y_f Z_L) e^{\lambda_3 l} (1+Y_f Z_L) e^{-\lambda_3 l} & \end{vmatrix}$$

By varying the amount of coupling as indicated by k_L , the voltage ratios as just computed can be variable. The following table shows examples of output for a few typical cases with unit amplitude input.

k_L	$B_1 l = wl \sqrt{(LC)} (l+k_L)$	$B_2 l = wl \sqrt{(LC)} (l-k_L)$	$\left \frac{v_2(0)}{v_1(0)} \right $	$\left \frac{v_2(l)}{v_1(0)} \right $	$\left \frac{v_1(l)}{v_1(0)} \right $
			$\left \frac{v_2(0)}{v_1(0)} \right $	$\left \frac{v_2(l)}{v_1(0)} \right $	$\left \frac{v_1(l)}{v_1(0)} \right $
0.6-----	$\frac{4\pi}{2\pi}$	$\frac{2\pi}{\pi}$	0	0	1
0.6-----	$\frac{2\pi}{2\pi}$	$\frac{\pi}{\pi}$	0	1	0
0.8-----	$\frac{3\pi/2}{2\pi}$	$\frac{\pi/2}{0.21\pi}$	0.5	0.87	0
0.99-----	$\frac{3.2\pi}{2\pi}$	0.21 π	About 0.7	About 0.7	About 0

What is claimed is:

1. A directional coupler comprising:

- (a) a semiconductive layer,
- (b) a thin insulating coating on said layer,
- (c) two substantially parallel conducting lines situated adjacent to said coating on the side away from said layer, said lines being spaced apart a distance which is substantially greater than the thickness of said insulating coating but substantially less than the thickness of said semiconductor layer, and
- (d) a conducting plane situated adjacent to said layer on the side away from said coating.

2. A directional coupler according to claim 1 wherein said conducting lines and said conducting plane are metallic.

3. A directional coupler according to claim 1 wherein the semiconductor of said semiconductor layer comprises silicon.

4. A directional coupler according to claim 1 wherein said thin insulated coating comprises a layer of silicon dioxide formed on the surface of said silicon.

5. A directional coupler according to claim 4 wherein said conducting lines and said conducting plane are metallic.

6. A directional coupler according to claim 4 wherein

said conducting lines and said conducting plane comprise thin layers of aluminum.

7. A directional coupler using the transmission line of claim 1 wherein a first signal is applied to one end of one of said conducting lines and a substantially proportional second voltage signal appears on at least one end of the other of said conducting lines.
